UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

HOSE SUPPORTER.

Application filed October 31, 1921. Serial No. 511,885.

To all whom it may concern:

Be it known that I, CARL J. HAZELTON, a citizen of the United States, residing at Worcester, in the county of Worcester and 5 State of Massachusetts, have invented a new and useful Hose Supporter, of which the following is a specification.

This is in part a continuation of my allowed application Serial No. 455,764 filed 10 March 26, 1921.

This invention relates to a hose supporter of the type in which a metallic loop is employed to grip the fabric between its two arms and a button carried by a tab usually depending from the upper part of the loop. As heretofore put on the market these clasps have had a serious fault due to the fact that when the stocking is gripped and put under strain, that strain comes 20 along a central vertical line and therefore is sustained primarily by only a very small number of vertical threads. The result, very frequently, is the production of so-called "runs" disfiguring and weakening the 25 hose. Another defect of the usual clasps on the market is that the rubber collet is put on a headed stud in such a manner that the head alone is depended upon to hold the collet in place. The result is that any 30 unusual strain transverse to the plane of the clasp is likely to dislodge the collet from its supporting element and ruin the whole device. This objection applies especially to that type of button or stud which has a 35 rubber covered top or head with only one round headed stud.

This invention is designed to overcome these defects without revolutionizing the appearance of the article. More specifically stated, the objects of this invention are to provide a rubber covered button of such a nature that the clamping grip between the button and the loop member takes place on an extended line transversely of a plurality of the wales of the hose fabric so that the strain on the fabric is equally distributed throughout a wide area. Thus a substantial number of threads, wales or stitches are simultaneously gripped and the 45 danger of injury to the hose fabric or the appearance of runs in the hose will be avoided or very much reduced; to provide a construction in which the rubber covering of the button is held firmly in position 50 by a solid body of rubber having two ad-

jacent heads of metal over an area at the front, so that even if the rubber becomes weak through use or age it cannot be pulled off its supporting elements; to provide a yielding transverse wall of rubber at the 60 lower front corner of the button for the stocking to engage and on which the stocking has its bearing, whereby the yield of this wall will reduce the strain on the stocking at this point and assist in preventing runs; to provide these features in such 65 form that it will be equally effective, in co-operation with the loop, to hold the fabric no matter at what angle the loop is applied; and to provide effective and inexpensive means for preventing the button from turning on its support so that the above mentioned objects will be maintained 70 after wear.

The invention also involves other features 75 of construction which tend to assist in accomplishing the above mentioned objects as will appear.

Reference is to be had to the accompanying drawings, in which

Fig. 1 is a front elevation of a stocking 80 supporter clasp constructed in accordance with this invention and showing it as it holds the stocking in position under strain;

Fig. 2 is a similar view showing the parts 85 with the stocking fabric removed;

Fig. 3 is a side elevation with the parts 90 in the same position;

Fig. 4 is a central vertical sectional view taken along the line 4-4 of Fig. 1;

Fig. 5 is a sectional view of the button 95 and its supporting base plate on the line 5-5 of Fig. 3;

Fig. 6 is a horizontal central sectional view of the same; and

Fig. 7 is a horizontal central sectional view of a modified form of button and base plate.

The hose supporter in the main figures of the drawing is illustrated as in use and 100 in a vertical position. The terms "top", "bottom", "front", etc. are, therefore, employed but these and similar terms being used for description are to be taken as relative and not as restrictive.

The hose supporter clamp comprises two members, first the loop member and second the button member, and these co-operate to grip or clamp the hose fabric when in place.

The invention is shown as applied to a 110

5 tallic loop 11. This loop 11 is provided with almost parallel but slightly converging side arms 12. These are connected across the end of the loop by a straight bar 14. These parts, of course, are all formed of a 10 single piece of wire or metal stamping and preferably are integral with each other. They form a button receiving loop at the bottom of the main loop 11.

essarily somewhat distorted by passing over the head of the button and back through the loop but this necessary distortion is minimized by the general convex and curved shape of the head which allows the section of the fabric passing over the button and through the loop to be positioned in a smooth even form.

Also supported by the loop 10 and hanging down behind the loop 11 is a piece 15 of textile material, usually in the form of non-elastic tape. This is provided on the bottom with a metal base plate 16 supported in vertical position in the usual or any desired way. This plate has the usual transverse perforations for receiving the tape 15.

The segmental shape of the shank of the collet also insures when the loop member is placed in co-operative clamping position that the loop member shall automatically assume its proper co-operative relation to the collet because even if the loop member is placed in position at an improper angle, it will rock or swing into proper position. The collet 80

Between the projections but spaced from them there are two rivets 18 located at a distance apart but at the same elevation. These are provided with heads 19 arranged symmetrically with respect to their shanks. These heads are of such diameter that they are spaced only a short distance apart.

The other forms of construction shown embody important features of the invention, particularly the wide transverse extended gripping surfaces of the loop and button members and the lower front yieldable wall of the button member, together with variations in the means for securing the collet to the base of the button member. 85 90

A rubber covering or collet 20 is applied to the shanks.

In the form shown in Fig. 7 two studs 38 are shown with their heads resting on a metal plate 39, which holds the rubber and positively spaces the studs. 95

The collet is of a peculiar and novel shape. It comprises a shank portion and a head portion. The shank is preferably of segmental cross section comprising the larger part of the circle and arranged with the flat area at the bottom as shown in Fig. 5. The front surface of the head is of generally convex form and is provided with a depression or groove 21 extending parallel with the bottom of the head. The bottom of this groove serves as a seat for the heads of the rivets 19 which are thus sunk well below the front of the head. This recess also causes the head to present two comparatively thin walls 22, the lower or bottom one of which in particular is, therefore, readily yieldable in an upward direction because instead of a solid rubber backing behind it, there is only the groove 21.

Although I have illustrated and described only two forms of the invention I am aware of the fact that other modifications can be made therein by any person skilled in the art without departing from the scope of the invention as expressed in the claims. Therefore, I do not wish to be limited to all the details of construction herein shown and described but what I do claim is:—

50 When, therefore, the clamping members are brought into co-operative relation with the hose fabric clamped therebetween as shown in Figs. 1 and 4 a longitudinal strain is placed upon the hose, the transverse bar
55 14 of the loop member firmly clamps the hose fabric against the bottom surface of the collet with the clamp or grip thus extended over a plurality of the wales or lines of stitches of the fabric. Thus the strain
60 on the fabric is widely distributed and there is little danger of the stitches being broken and runs caused as would be the case if the fabric were simply gripped at one or two

1. As an article of manufacture, a hose 105
supporter button comprising a metal plate,
a rubber collet thereon, a metal plate on the
front of said collet, and two rivets extend-
ing through the rubber collet and through
both plates to hold them together. 110

2. As an article of manufacture, a hose supporter button comprising two parallel plates, a rubber collet located between them and having a depression in which one of them is located, and means extending through the collet for fastening both plates thereto. 115

3. As an article of manufacture, a hose supporter button comprising two plates, a rubber collet located between them, and means extending through the collet for fastening both plates thereto. 120

In testimony whereof I have hereunto affixed my signature.

CARL J. HAZELTON
